UNITED STATES PATENT OFFICE.

WILLIAM D. McCULLOUGH, OF DETROIT, MICHIGAN.

CUSHION-SEAT.

1,254,333.

Specification of Letters Patent. Patented Jan. 22, 1918.

Application filed January 31, 1916. Serial No. 75,423.

To all whom it may concern:

Be it known that I, WILLIAM D. McCULLOUGH, a citizen of the United States of America, residing at Detroit, in the county 5 of Wayne and State of Michigan, have invented certain new and useful Improvements in Cushion-Seats, of which the following is a specification, reference being had therein to the accompanying drawings.

10 The invention relates to cushion seats for vehicles and has more particular reference to the means for securing the skirt of the cushion to the spring frame.

In the drawings:

15 Figure 1 is a perspective view of the seat with the cushion attached to the frame;

Fig. 2 is a vertical section showing the skirt and the initial operation of securing the same to the spring frame;

20 Fig. 3 is a similar view showing the second step in the operation;

Fig. 4 is a sectional perspective view showing the fastening completed; and

Fig. 5 is an elevation thereof.

25 A is the cushion and B is the depending skirt therefor which incloses the supporting spring frame C. It is desirable to provide means for quickly securing this depending skirt to said spring frame so that 30 it may be detached when desired, and to this end I have devised the following construction: D is a metallic strip secured to the lower edge of the skirt and extending around the same. This strip is provided at intervals with slots E therein which are aligned with the lower bar F of the frame C. G are bifurcated clips for embracing the bar F and insertion through the slots E from the inner side of the skirt. These clips may 35 be engaged as shown in Figs. 2, 3 and 4, and after the bifurcated prongs are pressed through the slots they are turned over as shown in Figs. 4 and 5. These prongs are 40 also fashioned so that the bent-over portion

is semi-circular and the two portions together produce the appearance of a button. 45

With the construction as described, the skirt may be readily attached to or detached from the frame C and without injury thereto.

50 What I claim as my invention is:—

1. The combination with a cushion of a depending skirt therefor, a spring frame for supporting said cushion having an edge bar adjacent said skirt, and bifurcated clips for 55 embracing said edge bar insertible through said skirt from the inside thereof and adapted to be clenched thereover.

2. The combination with a cushion and a depending skirt therefrom, of a spring frame 60 for supporting said cushion having an edge bar adjacent to said skirt, a slotted reinforcement for said skirt adjacent to said bar, and a bifurcated clip for embracing said bar insertible through the slot of said 65 reinforcement and adapted to be clenched outside of the skirt.

3. The combination with a cushion and a depending skirt therefor, of a spring frame for supporting said cushion having an edge 70 bar adjacent to said skirt, a marginal reinforcing bar secured to said skirt and provided with slots at intervals registering with said edge bar, and clips for embracing said edge bar insertible through said slots and 75 adapted to be clenched outside of the skirt.

4. The combination with a cushion of a depending skirt therefor, a skirt frame secured to and surrounding the lower edge of said skirt, being provided with slots at intervals, a spring frame inclosed by said skirt having an edge bar aligned with the slots in said skirt frame, and clips for embracing said edge bar insertible through the slots in said skirt frame and adapted to be clenched 85 over the same.

In testimony whereof I affix my signature.

WILLIAM D. McCULLOUGH.
